BEVERAGE DISPENSER OR SIMILAR ARTICLE

Richard T. Cornelius, Minneapolis, and James Robert Reichow, Edina, Minn., assignors to The Cornelius Company, Anoka, Minn., a corporation of Minnesota

Filed June 15, 1962, Ser. No. 70,566

Term of patent 14 years

(Cl. D2—3)

FIGURE 1 is a perspective view of a beverage dispenser, showing our design.

FIGURE 2 is a front elevational view thereof.

FIGURE 3 is a side view thereof, the opposite side having an appearance which is a reversal of this figure.

FIGURE 4 is a top view thereof.

FIGURE 5 is a rear view thereof.

FIGURE 6 is a fragmentary perspective view of a modified form thereof, wherein the sign is omitted, the remainder of the dispenser being identical to the form shown in FIGS. 1 through 5.

The dominant features of our design reside in the portions shown in full lines.

We claim:

The ornamental design for a beverage dispenser or similar article, substantially as shown and described.
